AUTOMATIC LUBRICATOR FOR ELEVATOR
GUIDE RAILS

Frederick Northausen, Coburg, Victoria, Australia

Application March 18, 1939, Serial No. 262,584

6 Claims. (Cl. 184—23)

This invention has reference to improvements in and relating to automatic lubricators for the slide bars or rods of elevators, lifts or the like. The said invention has been devised to provide a lubricator that will be comparatively cheap to manufacture, and readily applicable to various types of lifts in order to positively lubricate the said slide bars or rods thereof whilst the lift or elevator is in operation.

10 The said invention has further reference to that type of lubricator wherein said slide bars or rods are automatically and continuously lubricated whilst the lift or elevator is working, so that during the inoperative periods of said lift 15 or elevator, the lubricator ceases to function and thereby conserves the oil, while the excess of the latter which may be fed to said rod is led and directed back to the reservoir.

15 The invention is characterized in that the lubricator is in the form of a rotary element which is maintained in frictional engagement with the aforesaid slide bars or rods of the elevator the movement of which latter causes the element to rotate for such lubrication purposes, such rotation being specifically controlled in such a manner that the rotary element at times has a slipping motion.

20 There have been many and various types of this class of invention for the herein purpose.

25 My present invention however relates to specific improvements in that type having the following salient features:

25 The use of a reservoir containing oil, and resiliently mounted to retain an integral wiper shoe in direct contact with the slide bar or rod in the lift well, said reservoir having disposed therein a rotating element with its effective peripheral surface operating within a shaped slot in the said wiper shoe to be retained in frictional 30 contact with the slide bar or rod, the movement of the lift causing the element to rotate and distribute oil from the reservoir over the adjacent surface of the slide bar or rod. Means are also included in the shoe to direct the excess lubricant back into the reservoir. The rotary element may be provided with an eccentric or set off mounting whereby it is maintained by gravity in the operative position and in contact with the 35 slide bar or rod.

35 This said rotary element is fed with oil from the thereunder reservoir by an endless chain passing through said reservoir and over a boss formed on said rotary element, and means are 40 further herein employed for imparting a com-

bined rotary and slipping action to the aforesaid rotary element.

I have found in practice that several disadvantages arise from the use of certain types in this class of invention, chief among which are—

5 (a) Excess oil is delivered to the slide bar or rod due to the rapid rotation of the rotary element thus flooding the shaped slot in the wiper shoe. This results naturally in a waste of oil, through said excess oil dripping or running from 10 the main guide shoes of the elevator.

(b) The said rotary wheel or disc revolves at a high speed especially on occasions when the lift or elevator is running swiftly. This causes the said disc to vibrate and make intermittent tapping noises, which are transmitted to the elevator cage, and become objectionable.

15 The objects therefore of this invention are to overcome these disadvantages and also to provide means whereby an improved resilient mounting is employed between the lubricator casing and the said wiper shoe. Thus the coating members are retained in their operative positions in a positive manner. Briefly the invention resides in: (a) The provision of vanes or blades 20 fixedly or adjustably fitted to a disc or cheeked wheel immersed in the oil well. This disc wheel has a chain passing therearound which conveys the oil from said well to the rotary disc element 25 which contacts with the rod or bar aforesaid. These vanes or blades act as baffles and being immersed in the oil prevent the racing of the operative disc, thus maintaining the speed thereof within predetermined limits, irrespective of the speed of the elevator or lift. (b) Flexibly 30 mounting the casing of the device to the elevator shoe, by means of slotted lugs and therein co-acting bolts, pins or the like. Also a stepped bracket securely anchored to the said shoe, and by an upstanding arm, flexibly controlling by 35 coiled spring or springs, and set screw, the movement of the said casing in respect of the said rod or bar thus always maintaining a constant pressure between the casing and rod or bar. (c) The provision of a fibre, fabric or other tyre 40 around the operative shoe contacting disc, to further deaden any noises and such like.

45 In order however that the invention may be clearly understood the same will be described with the aid of the accompanying drawing in 50 which—

55 Figure 1 is a perspective view of the automatic lubricator constructed in accordance with this invention and as fitted in operative position.

Figure 2 is a side sectional view of said lubri-

55

cator, parts being shown in elevation for sake of clearness.

Figure 3 is a front elevation of said lubricator shown partly in section.

5 Figure 4 is a side sectional elevation of a modification of the said invention.

In carrying my invention into practical effect, the improved lubricator constructed in accordance therewith is automatic in operation, for the 10 reason that said lubricator does not function until the lift or elevator commences to move. The oil is thereby conserved and is prevented from splashing or being wasted while the lift or elevator is inoperative, and which waste is a 15 disadvantage and usually occurs with elevator lubricators of the class or type hitherto employed.

As illustrated in Figures 1, 2 and 3 it will be appreciated that a lubricator is employed and applied to each slide bar or rod supporting the 20 lift and is operatively disposed on the shoe thereof and thus moves in conjunction therewith and with the elevator. This slide bar or rod may of course be of any approved and suitable cross section. As illustrated the lubricator comprises a 25 casing 10 having an oil reservoir 11 in the bottom thereof.

This casing is provided with integral lugs 14 each made with a slot 16 through which pass a set 30 screw 18, interscrewing into holes formed in an intermediate place 17. The latter is sandwiched between said lugs 14 and the lugs 15 of the slideable shoe 12 of the rod or bar 13 and by set screws 17a, said plate 17 is securely anchored to the said slideable shoe 12. A spring washer 19 is disposed between the head of said set screw 18 and the intermediate plate 17 to maintain a grip 35 between said casing lugs and the anchored intermediate plate 17, while at the same time, by the slotted openings 16, allowing of a substantially 40 free slideable movement therebetween, to allow of self-adjustment between the herein operative elements.

In the hitherto mounting of the lubricator to the said slideable shoe 12, and associated members, 45 the same has been found to be insecure and insufficiently positive.

To overcome this disadvantage, and according to this invention, I securely anchor to the said elevator shoe 12, by set screws 20, a stepped 50 shaped bracket 21, the upper arm 21a of which is provided with an adjustable set screw 22. To the end of the latter is anchored a coiled spring 23, the opposite end of which is flexibly anchored to a lug 24 on the casing. (This spring may of 55 course be duplicated if desired.) The purpose of this bracket and spring is to flexibly control the movement of the lubricator proper and take up any vibration or wear that may occur between the same and the rod or bar, and also to positively 60 maintain said members in operative engagement with each other.

Disposed within the main casing 10 is a rotatable element comprising a wheel or disc 25 of 65 suitable diameter which is carried in a bracket 26 arranged at an inclination within said casing and suspended from the top thereof. This bracket comprises spaced inclined arms uniting at their upper ends on a transverse spindle or axle 27 the outer ends of which seat in recess 70 28 formed in the upper edges of the side walls of said casing 10. The lower ends of said bracket support the axle or spindle 29 of the rotary wheel or disc 25 which thereby is offset or out of vertical central alignment in relation to the supporting 75 pivotal axis 27 thereof. This wheel or disc 25

is formed at one side with a boss, stem or the like 30, positioned between spaced collars 31-32. These latter provide an annular groove in which is mounted an endless chain 33 or other flexible medium to depend into the oil reservoir 11 and which during rotation, upwardly conveys the oil to the said disc or wheel 25. This flexible medium in its lower loop carries a double disc or cheeked wheel 34, the outer faces of which are provided with blades or vanes 35. These latter may be 10 fixed or adjustably and removably fitted to said faces by set screws or bolts 35a and are thus enabled to be angularly positioned as may be desired. These blades or vanes 35 act as baffles to retard or control the rotation of the disc 15 wheel should the same tend to rotate at an excessive speed through the racing of the thereto driven disc wheel contacting with the rod or bar aforesaid, and impart to the latter a part rolling and part slipping movement, that is to say, when 20 an increased speed of the elevator beyond what may be termed the normal, is reached, the disc wheel 25 will commence to slip being rotationally retarded by the bladed element 34-35, hence imparting a combined part rolling part slipping 25 movement to said disc or wheel 25, thus controlling the flow of oil, and preventing the excessive feed of same to the slide bars or rods 13, resulting in a slow but positive feed of oil thereto, and overcoming flooding of such feed. 30

The adjustment of the blades or vanes however is to be so made as not to excessively retard such rotation. If such were allowed to take place, the disc or wheel 25 would cease rotation, 35 and such would result in wear to such disc or wheel 25 to such an extent as to form a flattened portion on its periphery, such of course being highly detrimental to its positive and free operation of such element.

The wiper shoe 36 of the herein invention is mounted on the casing 10 and is formed with a central vertical slot or opening 37 into which a portion of the periphery of the disc or wheel 25 is adapted to project whereby said disc or wheel will contact directly with the slide bar or rod 13. 45 As the spindle or axle 29 of the disc or wheel 25 is offset in relation to the supporting axis 27 of the bracket, a gravitational effect is achieved for the reason that the wheel or disc tends to swing forwardly and thereby retain the portion of said disc projecting through the slot or opening 37 in the wiper shoe 36 directly and constantly in contact with the slide bar or rod 13. 50

Further if desired, a tyre 25a may be fitted to 55 said disc wheel, same being made of fibre, fabric or such like wearable and sound deadening material, to reduce or eliminate noise and such like.

Means may be employed and provided on the wheel or disc 25 to vary or control the quantity 60 of oil to be delivered through the medium of the endless chain from the reservoir to the surface of the disc or wheel.

The wiper shoe 36 fitted to the face of the casing 10 is formed with spaced inclined recesses 65 40 in its side walls which extend inwardly to vertical grooves 41 cut in the corners of the side walls and the rear wall of said shoe. The rear of the latter is provided with a flange 42 to seat against the adjacent wall of the casing. An opening 43 is left between the rear wall of the casing and the flange 42 (as shown in Figure 2) whereby superfluous oil from the shoe and slide bar, accumulated in the upper recesses 40 is allowed to percolate into the corner grooves 41 and pass through and into said opening 43, and there- 70 75 80 85 90 95

by return to and collect in the reservoir 11, for reuse.

The resiliently mounted casing 10 provides for a constant engagement of the rotatable disc or wheel 25 with the slide bar or rod 13, and when the lift is moving in either direction the frictional engagement between the said disc 25 and slide bar or rod 13 causes the said disc to rotate, and the chain or the like mounted therewith is moved through the oil in the reservoir 11 to pick up and deliver a constant supply thereof to the said disc or wheel 25, and which by centrifugal force is deflected to the peripheral face edge thereof to be delivered during the rotation of said disc directly on to the slide bar or rod 13, the operation being continuous whilst the lift is moving in either direction.

The quantity of oil fed on to the slide bars or rods 13 depends on the pressure with which the wiper shoe 36 is forced against the bar or rod 13 and quantity of oil lifted by the chain or flexible member 33.

This pressure is controlled by the adjustable spring 23 and stepped bracket 21 and associated members. In combination with the latter the oil is controlled by the vane or bladed element 34—35 as aforesaid.

Should however lubrication be temporarily excessive the surplus oil will find its way back to the reservoir 11 through the slots or openings 40, 41, 43 in the wiper shoe.

As illustrated in Figure 4 the lubricator may be operated without the chain 33 or like flexible element and in this application the rotary disc or wheel 25 may, if desired, be enlarged and part of its periphery submerged in oil within the reservoir 11.

To this disc or wheel 25 is fitted the aforesaid blades or vanes 34—35 the purpose whereof is identical with that as afore-described. In the absence of the chain 33, the oil in this case is lifted by and during the rotation of the disc 25 and distributed directly on to the slide bar or rod, in the manner aforesaid.

The excess oil in this case, which may be fed to the slide bar or rod 13, is returned through the slots, openings or passages 45—46 (which are upwardly positioned in the wiper shoe 36), in a similar manner to those referenced 40, 41, 43, as before described.

A lubricator of the class previously and herein described is automatic in action and operation, only during the movement of the lift or elevator, and it will of course be obvious that mechanical improvements and modifications may be made and embodied therein without departing from the ambit, spirit and scope of the invention.

I claim:

1. An automatic lubricator for each slide bar of an elevator or the like, comprising a casing mounted adjacent to the said slide bar on the elevator, a rotary element in frictional engagement with each respective slide bar during the movement of the elevator to impart lubrication to the said bar, the said rotary element being disposed above an oil reservoir, means to deliver such oil to the rotary element, and means for controlling and regulating the speed of the said rotary element to prevent excess feed of such oil when the elevator speed is increased.

2. An automatic lubricator for each slide bar of an elevator or the like, comprising a rotary flanged element within a casing, the said element being mounted adjacent to the said slide bar on said elevator, the said element being in frictional

engagement with its respective slide bar during the movement of the elevator in either direction to impart lubrication to the said slide bar, a cheeked boss on the said rotary flanged element, said element being mounted on a spindle, angularly positioned brackets carrying said spindle, a pivot pin in the head of the main casing gravitatively carrying the said brackets and said element, an endless flexible chain member coacting on the said boss extending into an oil reservoir, and a rotary bladed element freely carried within the lower portion of said flexible chain member.

3. An automatic lubricator for each slide bar of elevators or the like, comprising a casing mounted adjacent to the said slide bar on said elevators, a rotary flanged element housed within said casing and in frictional engagement with the respective slide bar, an endless chain passing over a boss of the said rotary flanged element, a cheeked element freely carried in the lower loop of said chain and blades adjustably fitted to said cheeked element to vary their angularity and to impart a baffling effect to the said cheeked element and associated members.

4. An automatic lubricator for each slide bar of an elevator or the like, comprising a casing mounted adjacent to the said slide bar and on said elevators, a rotary flanged element housed within said casing and in frictional engagement with the respective slide bar, an endless chain passing over a boss of the said rotary flanged element for conveying lubricant from an oil reservoir, a rotary element carried in the lower loop of said chain, a shaped wiper shoe on the front face of the said casing partially embracing the said slide bar, a slot within said shoe through which the said rotary flanged element partially projects and coacts against the said slide bar, a stepped bracket anchored by one arm to the said elevator shoe, a spiral spring fitted and anchored through a set screw between the upper companion arm of the said stepped bracket and the said lubricating casing to maintain flexible connection therebetween, and slotted foot lugs coacting through set screws and spring washers, within the elevator shoe maintaining a substantial slidable movement therebetween.

5. An automatic lubricator for each slide bar of an elevator or the like, comprising a casing mounted adjacent to the said slide bar and on the said elevator, a lubrication reservoir in said casing, a rotary element disposed in said reservoir of said casing with a portion of its periphery immersed in the oil in said reservoir, the said element being maintained in contact with the slide bar whereby during its rotation oil is fed to the said slide bar, and blades directly fitted to the said rotating element to impart a halting effect thereto and prevent racing thereof.

6. An automatic lubricator for each slide bar of an elevator or the like, comprising a casing mounted adjacent to the slide bar and on the said elevator, a rotary flanged element within said casing, brackets pivotally held and gravitatively and angularly positioned within the said casing by a spindle carrying the said rotary flanged element, an endless flexible chain coacting on a boss of the said rotary element and depending within an oil reservoir for delivering lubricant to the said flanged element, a rotary element in the lower loop of said chain and driven thereby, and sound deadening means associated with said rotary flanged element.
